FRAME AND SCREEN CONSTRUCTION FOR
SCREEN PRINTING

David Jafia, Fair Lawn, and Matthew L. Jaffa, Rutherford, N.J., assignors to Precision Screen Machines Co. Inc., Hawthorne, N.J., a corporation of New Jersey

Filed Jan. 12, 1962, Ser. No. 165,922
10 Claims. (Cl. 101—127.1)

This invention relates in general to art of screen printing, and more specifically to an improved screen frame construction and printing screen therefor.

An object of this invention is to provide an improved frame construction for stretching a printing screen drum tight thereon.

Another object is to provide an improved screen frame construction having novel means for adjusting any segment of a design in a screen stretched thereover and in any direction to improve the fit or registration of one color to another during printing.

Still another object of the invention resides in an improved frame and screen construction whereby the screen can be readily attached or removed from the frame in a relatively simple and expedient manner.

A feature of this invention resides in the provision that the improved frame construction and screen therefor are relatively simple in construction and positive in operation.

Still another feature resides in the provision whereby the frame construction and screen permits removal of the screen after a printing operation so that it can be rolled and stored, thus minimizing storage areas for the storing of such screens.

Other features and advantages will become more readily apparent when considered in view of the drawings and description in which:

FIG. 1 is a top plan view of the screen frame construction of this invention illustrated without screen.

FIG. 2 is an end view of the frame construction of FIG. 1 with screen attached.

FIG. 3 is a section view taken along line 3—3 of FIG. 2.

FIG. 4 is a detail plan view of the improved screen construction of this invention.

FIG. 5 is an enlarged sectional view taken along line 5—5 of FIG. 4.

FIG. 6 is a fragmentary side view of a modified frame construction as used with a wire screen.

FIG. 7 is a fragmentary sectional view of still another modified form of the invention.

FIG. 8 is a plan view of the head of an adjusting bolt.

FIG. 9 is a plan view of a modified bolt head.

FIG. 10 is a modified screen frame of the type illustrated in FIG. 1.

Referring to the drawings, the improved frame or screen stretcher 20 comprises an inner frame 21 formed of rectangularly disposed frame side 22 and end 23 members. Generally this inner frame 21 may be made of wood or other suitable material. Connected to the outer periphery of the inner frame 21 is an outer stretcher frame 24 as shown in FIGS. 1, 2 and 3, the stretcher frame 24 including side and end sections 25, 26, respectively, connected to the outer surfaces of the corresponding side and end members 22, 23 of the inner frame 21. Each of the stretcher frame sections 25, 26 comprise an angle member having a vertical and horizontal leg or flange 27, 29, respectively. The vertical leg 27 of each outer frame section 25, 26 is connected to the outer periphery of the corresponding inner frame member by suitable fasteners such as screws and the like. In the illustrated embodiment it will be noted that the inner frame members 22, 23 extend slightly beyond the ends of the stretcher frame sections 25, 26 connected thereto. As shown in FIG. 3, the

2

bottom of the vertical leg 27 portion is flush with the bottom of the corresponding inner frame member.

The horizontal leg 29 of each section extends outwardly from the inner frame 21 and a plurality of marginal apertures or notches 30 are spaced longitudinally along each of the horizontal flanges 29.

The screen 31 adapted to be stretched over the frame 21, is shown in FIGS. 4 and 5. Generally screen 31 may be formed either of silk or wire mesh depending on the nature of the printing to be performed. In either event, the screen construction of this invention comprises a printing portion having looped hems 33 extending substantially co-extensive with the respective sides of the printing portion.

15 In accordance with this invention the looped hem 33 along each side of the screen is formed by a tape 34 that is reversely folded, as seen in FIG. 5. Intermediate the width of the tape 34 and extending longitudinally thereof is a sewn seam 35 to secure the folds 34A and 34B together, the seam 35 and closed end of the tape defining therebetween the loop 36. Hem 33 is attached to the screen 31 by disposing the end portion of screen 31 between the free ends 37, 38 of tape 34.

As shown in FIG. 5, a resin adhesive or other suitable 25 thermoplastic bonding strip or agent 39 and the like may be disposed between each free end 37, 38 of the tape 33 and the screen 31. Thus, with the application of heat and pressure over the ends of the tape, a firm connection is had between the hem 33 and the screen portion 31.

30 In accordance with this invention the screen 31 is stretched and adjusted to the frame 21 described by a plurality of holding fixtures 40 in a novel manner. As seen in FIGS. 2 and 3, each fixture 40 includes essentially a split collar 41 which is preferably formed as a rectangular block having a split or C-shaped opening 42 adapted to receive the looped hem 33 of the screen 31. Each block 41 also is provided with a tapped hole 43 extending therethrough to one side of the opening 42.

35 A bolt 44 adapted to be threaded into the tapped hole 43 of the block adjustably connects the block 41 to the frame 24. In accordance with this invention, the bolt 44 of each fixture 40 is adapted to be received in one of the notches 30 of the stretch frame 24. As shown in FIG. 3, the flanges 29 of the stretch frame 24 and the split blocks 41 are each proportioned so that in the assembled position the blocks 41 are disposed in sliding contact with the vertical leg 27 of the respective frame section 24.

40 Each bolt 44 is provided with an enlarged head portion 45 which is adapted to sit on the flanges 29 of the stretcher frame 24. If desired, a washer 46 may be interposed between the head 45 of the bolt and the flange 29. As shown in FIG. 8, the head 45 of each bolt 44 is provided with a socket 47 for receiving a tool, e.g. an Allen wrench, by which the bolt 44 may be turned to effect 45 adjustment of the split collar block 41 relative to the frame 24. As an alternate construction the bolt 44A may be formed with a hex head 45A and/or a combination of hex head and socket 47A.

To secure the screen 31 to the frame 24, the looped end 60 of the hem 33 is inserted into each of the openings 43 of the split collars 41 common to one side of frame 24. A retaining rod 48 is then inserted into the hem 33 within the split collar 41. As shown in FIG. 3, it will be observed that the diameter of the rod 48 is larger 65 than that of the slit 49 through which the hem 33 is inserted into the split block 41. Thus, with the rod 48 in position, as seen in FIGS. 2 and 3, the screen 31 is held in position along the side so secured. Each side of the screen 31 is similarly connected to the frame. 70 Therefore, it will be apparent that by turning each of the adjusting bolts 44 to raise or lower the respective split

collars 41 accordingly, the fabric of the screen 31 is stretched tightly across the bottom of the frame 21.

For the foregoing description it will be readily apparent that the screen 31 can be readily attached and detached from the frame 24. Thus after wash up and after the printing is completed, the respective rods 48 may be removed from the hem 33 of the screen 31, and the screen being then removed may be rolled up for economical storage in a sealed tube. If desired, a number or a set of such screens may be rolled and stored in a single tube. Being able to remove the screen from its frame after each printing operation avoids the possibility of screen sag resulting from maintaining the screen stretched on the frame for prolonged periods. When the design of a given screen is needed again, it becomes a simple matter with the described construction to lay out the original art work and remount each screen to a master frame and adjust each to perfect register.

In the event it is desirable to utilize a wire cloth for a screen instead of silk or nylon, the construction is similar to that herein described, except that the free ends of the hem or hem tape are attached to either side of the screen by either soldering or sewing. Also as seen in FIG. 6, a compression spring 50 is placed about the adjusting bolts 51 between the head 51A and the flange 52 of the stretcher frame 53. Thus when the wire cloth is stretched over the frame 53 it will have a tendency to be slightly resilient. The wire screen thus mounted, has the stability of wire together with the ability to resist pressure stretch.

FIG. 7 illustrates a modified frame section 60. In this form, the inner and outer frames are integrally formed in an extruded structural shape as a continuous bar. Thus, to form the frame for a screen, the bar need only be cut to length and assembled to form a rectangular closed figure of any suitable size.

As shown in FIG. 7, the extruded member is provided with an F-shaped cross-sectional shape 60. Essentially it consists of a horizontally disposed back 61 having connected thereto an inner and outer depending arm portion 62, 63, the former extending slightly beyond the latter. The free end of each arm 62, 63 is provided with a rounded surface 62A, 63A.

As with the stretcher frame segments of FIGS. 1 to 3, the laterally extending portion 61A of the modified frame 60 is provided with apertured portions for receiving the adjusting bolt 44 of the split collar 41 in the manner as hereinbefore described.

Referring to FIG. 7 it will be noted that the face of the split collar 41 is disposed in contacting relationship with the outer surface 63B of the outer arm 63. With the screen 65 assembled to the frame 60 in a manner as hereinbefore described, the length and end shapes of each arm 62, 63 permit the extended ends of the screen to be guided thereover without snagging, or catching. In all other respects, the construction of the holding fixtures and their particular mode of operation in this form of the invention is the same as that described with reference to FIGS. 2 and 3. Therefore, the description thereof need not be repeated.

FIG. 10 illustrates a modified frame construction 120 of the type disclosed in FIG. 1. It comprises an inner frame composed of side and end members 122 and 123. Connected to the inner frame members 122 are the angle members 125 of the outer frame. Members 125 are provided with spaced notches 130 as herein described with reference to FIG. 1. In this form the end members of the outer frames are omitted. In all other respects the operation and construction thereof is similar to that of FIG. 1 herein, and need not be further described.

An important feature of this invention resides in the provision that the retaining rod 48 is flexible, i.e. it is free to flex in the event one of the split collars 41 spaced therealong is tightened more or less than the next adjacent collar. For this reason portions of the screen

may be adjusted or stretched independently of other portions thereof. Thus the ability of the rod 48 to flex under certain conditions greatly enhances the adjustability or orientation of the screen.

5 While the instant invention has been disclosed with reference to a particular embodiment thereof, it is to be appreciated that the invention is not to be taken as limited to all of the details thereof as modifications and variations thereof may be made without departing from the 10 spirit or scope of the invention.

What is claimed is:

1. A stencil comprising an inner frame, an outer stretcher frame connected to the outer periphery of said inner frame, said outer frame consisting of an angle having a vertical and horizontal leg portions, means connecting the vertical leg portion of said stretcher frame to the inner frame so that the horizontal leg portion extends laterally outwardly of the connected inner frame member, said stretcher frame having a plurality of notches spaced therearound, a printing screen adapted to be stretched over said inner frame, said screen having looped hem portions about the periphery thereof, and a holding fixture located at each of the notches spaced along the stretcher frame for securing and stretching said screen 20 over said inner frame, each of said holding fixtures including a split collar block adapted to receive the hem of the screen, a holding rod extended through the looped hem within the collar blocks spaced along the side of said stretcher frame for retaining the hem in position within 25 said collar blocks, and adjusting means for securing each of the collar blocks to the stretcher frame, said latter means including a threaded bolt adapted to engage a threaded bore in said collar block whereby said screen is stretched and adjusted by tightening and loosening the 30 bolts accordingly to raise and lower the respective blocks independently of one another.

2. The invention as defined in claim 1, wherein said split collar block is disposed in sliding engagement with the vertical leg of the stretcher frame.

40 3. A stencil comprising an inner frame, an outer stretcher frame connected to the outer periphery of each of said inner frames, said outer frame consisting of an angle bar having a vertical and horizontal leg portion, means connecting the vertical leg portion of said outer frame to the inner frame with the horizontal leg portion extending laterally outwardly of the connected inner frame member, said stretcher frame having a plurality of notches spaced therearound, a wire screen adapted to be stretched over said inner frame, said screen having looped hem portions about the periphery thereof, and holding fixtures located at each of the notches spaced along the outer frame for securing and stretching said wire screen over said inner frame, each of said holding fixtures including a split collar block adapted to receive the hem of the screen, a holding rod extending through the looped hem within each collar block spaced along a side of said stretcher frame for retaining the hem in position within said collar blocks, adjusting means for securing each of the collar blocks to the outer frame, said latter means including a headed bolt adapted to engage a threaded bore in said collar block whereby said screen is stretched and adjusted by tightening and loosening the bolts accordingly to raise and lower the respective blocks independently of one another, and a spring disposed between the head of the bolt and horizontal leg of the outer frame to impart resiliency to said screen.

4. A stencil comprising an inner frame including rectangularly disposed side and end members, an outer stretcher frame connected to the outer periphery of each of said side and end members, said stretcher frame including side and end sections connected to the corresponding side and end members of said inner frame, each of said stretcher frame sections including an angle bar having a vertical and horizontal leg portion, means connecting the vertical leg portion of each stretcher frame sec-

tion to the corresponding member of said inner frame so that the horizontal leg portion extends laterally outwardly from the connected inner frame member, each of said stretcher frame sections having a plurality of spaced notches formed therein, a screen containing the stencil design adapted to be stretched over said inner frame, said screen having looped hem portions about the periphery thereof, and holding fixtures located at each of the notches spaced along the stretcher frame sections for securing and stretching said screen over said inner frame, each of said holding fixtures including a split collar block adapted to receive the hem of the screen, a holding rod extended through the looped hem within each collar block spaced along each stretcher frame section for retaining the hem in position therein, and adjusting means including a threaded bolt adapted to engage a threaded bore in said collar block whereby said screen is stretched and adjusted by tightening and loosening the bolts accordingly to raise and lower the blocks independently of one another.

5. A stencil comprising a stretcher frame comprising rectangularly disposed side and end frame segments, each of said segments including an integrally formed spaced depending inner and outer arm portion, each of said arm portions having a rounded end, and said inner arm portion being longer than the outer arm portion, a screen having looped hems stretched over the depending arm portions, and a plurality of holding fixtures for stretching and adjusting said screen to said frame, said holding fixtures being spaced about the periphery of said frame, each fixture including a split block having an opening therein, means for securing the hem of said screen in the opening of said blocks, and an adjusting bolt connecting said split block to said frame whereby said screen can be stretched and adjusted by the respective adjustments of the individual collar blocks.

6. A stencil comprising a stretcher frame comprising rectangularly disposed side and end frame segments, each of said segments including an extruded structure having integrally formed spaced depending inner and outer arm portions, each of said arm portions having a rounded end, and said inner arm portion being longer than the outer arm portion, said segment extending laterally from said outer arm portion, a screen having looped hems stretched over the depending arm portions of said frame, and a plurality of holding fixtures for stretching and adjusting said screen to said frame, said holding fixtures being spaced along the extended portion of said segments about the periphery of said frame, each fixture including a split block having an opening therein, said block being disposed in sliding engagement with the surface of the outer arm portion, means for securing the hem of said screen in the opening of said blocks, and an adjusting bolt connecting said split block to the extended portion of said frame whereby said screen can be stretched and adjusted by the respective adjustments of the individual collar blocks.

7. An improved stenciling screen comprising a rectangular screen portion and a looped hem extending about each side of the said screen portion, said looped hem terminating short of the corner portions of said sides and including a reversely folded tape, a sewn seam connecting the reverse folds of said tape only intermediate the width thereof to define the loop and means connecting the free ends of said tape to both sides of the design portion of said screen.

8. An improved stenciling screen comprising a rec-

tangular screen portion and a looped hem extending about each side of the said screen portion, said hem terminating short of the ends of the sides of said screen, and said looped hem including a reversely folded tape, a sewn seam connecting the reverse folds of said tape only intermediate the width thereof to define the loop, and a resin strip disposed between each free end of said tape and the screen disposed therebetween so that upon the application of heat and pressure said tape will be fused to said screen portion.

10. 9. A stenciling screen comprising a rectangular stretcher frame, a rectangular stenciling screen adapted to fit said frame, a looped hem connected to each side of said screen, said frame having an outwardly extending flange along each side thereof, and a plurality of separate and distinct holding fixtures connected to each of said flanges, each of said fixtures including a collar block, said blocks being spaced one from the other along their respective flanges, and each block having a C-shaped opening adapted to receive the looped hem of said screen, a rod fitted through the looped hem of said screen within said openings of said blocks for retaining the screen therein, and a single adjusting bolt for connecting and adjusting each of said blocks to their respective flanges whereby said screen is stretched and adjusted by the adjustments of said bolts accordingly to raise and lower the respective blocks independently of one another.

15. 10. A stenciling screen comprising a rectangular stretcher frame, a rectangular stenciling screen adapted to fit said frame, said screen having a looped hem connected along each side of said screen, said frame having an outwardly extending flange along each side thereof, and a plurality of separate and distinct holding fixtures spaced along the flange of each side of said frame, each of said fixtures including a split collar block, each of said blocks having a split opening adapted to receive the looped hem of said screen, a rod fitted through the looped hem along each side of said screen within said blocks spaced along the flange of the adjacent side of said frame for retaining the screen therein, said rod having a diameter greater than the split of said opening, and a single adjusting bolt for connecting and adjusting each of said blocks to said flange whereby said screen is stretched and adjusted by adjusting said bolts accordingly to adjust the respective blocks independently of one another, said bolt having an enlarged head, and a spring disposed between the flange and head of said bolt to render said screen resilient.
